UNITED STATES PATENT OFFICE.

OTTO ROTHARDT, OF COLOGNE-MULHEIM, GERMANY.

INTERNAL-COMBUSTION ENGINE.

Application filed March 12, 1923. Serial No. 624,557.

To all whom it may concern:

Be it known that I, OTTO ROTHARDT, a citizen of Germany, residing at Cologne-Mulheim, No. 48 Prinz-Heinrichstrasse, 5 Rhenish Prussia, Germany, have invented certain new and useful Improvements in Internal-Combustion Engines; and I do hereby declare the following to be a full, clear, and exact description of the invention, such 10 as will enable others skilled in the art to which it appertains to make and use the same.

The invention relates to internal combustion engines of the kind adapted to be operated both by light as well as by heavy oils 15 and permitting an immediate changing-over from the light oil working in which a carburettor is used, to the heavy oil working which is executed by a direct injection of the 20 fuel.

The invention has for its object to provide an engine of the said character with which the parts necessary for the two kinds of working are arranged in such a manner 25 as to secure an undisturbed and economical working in each case.

According to the invention, this object is attained by mounting the spark plug and the fuel injecting nozzle in close proximity 30 of each other at one side of the cylinder cover and by arranging the outlet ports of the fuel nozzle so as to extend horizontally and towards the other side of the cover, thus permitting the fuel leaving the nozzle by 35 the said ports to be injected fan-shapedly into the interior of the combustion chamber in directions away from the spark plug.

The subject-matter of the invention is illustrated, by way of example, in the accompanying drawing in which:

Fig. 1 is a plan, seen from below, of the cylinder cover of an engine constructed in accordance with the invention; and

Fig. 2 is a section on the line I—I of

Fig. 1.

Mounted in the cover A' of the cylinder A are the main valves of the engine, viz., the inlet valve B and the outlet valve B', as well as the fuel injecting valve C. The 50 valves B and B' are shown to lie on the same diameter, but they may equally well be arranged in any other suitable manner. The fuel injecting valve C is mounted near the marginal portion of the cover at one side 55 of the same. It opens into an ignition chamber C' which forms a nozzle D estab-

lishing communication with the interior of the cylinder A or the combustion chamber of the latter, respectively. The spark plug F is likewise mounted in the cover in close proximity of the nozzle and at the same side of the cover. The body of the nozzle D possesses a series of ports E arranged on a circle and extending horizontally in directions away from the spark plug F so that the jets of fuel will expand fan-shapedly into the combustion chamber.

As will be readily understood from the following, the described relative arrangement of the spark plug and fuel nozzle and the peculiar construction of the latter as regards its outlet ports affords most favorable conditions for working alternately with a carburettor and with direct fuel injection.

In order to work economically when running the engine by injected heavy oils, it is necessary to produce high compression pressures so as to dispense with the incandescent surfaces otherwise necessary for igniting the fuel, and to allow the fuel jets which are mainly ignited by the air, to move freely for a certain distance before they will strike against surfaces so that they may thoroughly mix with air on that way. With regard to the working with light oils using a carburettor and lower compression pressures for avoiding self-ignitions, it is further necessary that the igniting device is protected against a direct contact with the jets of heavy oils as otherwise ignition troubles will be unavoidable. Hitherto, it has been customary to protect the spark plug which is only temporarily used, by means of an interposed valve or another shutting-off device, but this remedy possesses the drawback that one more member has to operate for changing-over from one kind of working to the other, thus rendering the changing-over more complicated and slower.

Now, with the construction according to the present invention, the fuel is allowed to come into touch with the necessary combustion air without striking too early against surfaces. Besides, the spark plug is securely protected from a direct contact with the ejected fuel jets, and the very hot flame which is produced when working with heavy oils will not be able to heat the spark plug too strongly, since the gases will reach the spark plug only after a certain time, namely, when the heavy oil jets are return-

ing from the opposite wall of the combustion chamber and have thus been subjected already to a certain cooling action. Finally, with the mounting shown of the spark plug, 5 the wave upset by the explosion will be prevented from injuring the insulation of the plug by striking unhinderedly against the same.

Having thus described my invention, what 10 I claim as new and desire to secure by Letters Patent, is:—

In an internal combustion engine, a cylinder, a cylinder cover, and a combustion chamber, a spark plug mounted in said 15 cover at its marginal portion, a fuel in-

jecting nozzle mounted in the cover and projecting within the chamber immediately adjacent the spark plug, the body of said nozzle being formed with a series of horizontally opening ports in that side of the 20 nozzle remote from the spark plug, the arrangement of the ports serving to eject the fuel in jets of fan-shaped outline in a direction away from the spark plug, whereby the imperforate portion of the nozzle acts 25 to prevent the plug being reached either by the direct or reflected fuel rays.

In testimony whereof I have signed my name to this specification.

OTTO ROTHARDT.
